DESIGN FOR A COMBINATION COMB AND
SAFETY HAIR CUTTER

Max Lazar, New York, N. Y.

Application December 22, 1947, Serial No. 143,283

Term of patent 3½ years

(Cl. D86—8)

To all whom it may concern:

Be it known that I, Max Lazar, a citizen of the United States of America, and a resident of the city of New York, in the county of New York and State of New York, have invented a new, original, and ornamental Design for a Combination Comb and Safety Hair Cutter, of which the following is a specification, reference being had to the accompanying drawing, forming a part thereof:

Figure 1 is a front elevation of a combination comb and safety hair cutter, showing my new design.

Figure 2 is a reversed view of the combination comb and safety hair cutter shown in Figure 1, a portion of the guard plate being shown broken away, and

Figure 3 is an enlarged section taken through line 3—3 of Figure 2.

I claim:

The ornamental design for a combination comb and safety hair cutter, substantially as shown.

MAX LAZAR.
